Primary Examiner — Catherine S Posthauer*(74) Attorney, Agent, or Firm* — NIXON PEABODY LLP**(57) CLAIM**

The ornamental design for a hinged overcap as shown and described.

DESCRIPTION

FIG. 1 is a top perspective view of a hinged overcap in a closed position, showing the new design.

FIG. 2 is a top perspective view of a hinged overcap of FIG. 1 in an open position.

FIG. 3 is a back view of the hinged overcap of FIG. 1.

FIG. 4 is a front view of the hinged overcap of FIG. 1.

FIG. 5 is a first side view of the hinged overcap of FIG. 1.

FIG. 6 is a second side view of the hinged overcap of FIG. 1, which is the opposite of the first side view.

FIG. 7 is a top view of the hinged overcap of FIG. 1; and, FIG. 8 is a bottom view of the hinged overcap of FIG. 1.

The broken lines are shown for the purpose of illustrating parts of the article that form no part of the claim.
